(57) CLAIM

The ornamental design for a deck mounted plant hanger, as shown and described.

DESCRIPTION

FIG. 1 is a front perspective view of the new design showing the mounted on a deck;

FIG. 2 is a front perspective view of the new design;

FIG. 3 is a front elevational view thereof;

FIG. 4 is a back side elevational view thereof;

FIG. 5 is a right side elevational view thereof;

FIG. 6 is a left side elevational view thereof;

FIG. 7 is a top side plan view thereof;

FIG. 8 is a bottom side plan view thereof;

FIG. 9 is a front perspective view thereof, with an enlarged detail of a railing strap thereon; and,

FIG. 10 is a front perspective view thereof, with an enlarged
detail of the deck mounted plant hanger thereon.

The broken lines shown in the figures represent portions of the deck mounted plant hanger that form no part of the claimed design.
